UNITED STATES PATENT OFFICE.

WILLIAM EZRA DOANE, OF GRIGGSVILLE, ILLINOIS.

RAILWAY TIE AND RAIL-FASTENING DEVICE.

Application filed August 6, 1923. Serial No. 655,971.

To all whom it may concern:

Be it known that I, WILLIAM EZRA DOANE, a citizen of the United States, and a resident of Griggsville, in the county of Pike and State of Illinois, have invented certain new and useful Improvements in Railway Ties and Rail-Fastening Devices, of which the following is a specification.

This invention relates to an improvement in metallic railway ties and fastening devices for securing the rails thereto.

The object of the invention is to provide a railway tie and fastening device of this character whereby the rails may be readily secured in position upon or taken from the ties without the necessity of employing special tools or expensive and complicated securing devices.

Another object is to provide a device of this character and having these advantages and which is also of simple and durable construction, reliable and safe in operation and easy and comparatively inexpensive to manufacture.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a perspective view, showing the preferred embodiment of the invention;

Figure 2 is a view thereof in transverse vertical section;

Figure 3 is a bottom plan view; and

Figures 4 to 7 are detail perspective views of the several parts of the fastening device.

Referring to the drawings wherein for the sake of illustration is shown the preferred embodiment of the invention, the numeral 10 designates one of the ties employed in conjunction with the present invention, and

as shown it consists of an inverted channel-shaped piece of metal such as steel or any other suitable material. The rails which are designated by 11 have their base section resting directly on the tops of the inverted channel shaped ties. Below each rail 11, each tie 10 is provided with a longitudinally extending slot 12 which is enlarged adjacent one end, as at 13, to provide an opening somewhat larger than the slot and communicating therewith.

Fastening devices are employed for secur-

ing the ties to the rails and are all of identical construction, and each includes a fixed block 15 provided at one end with a rail engaging shoulder 16 adapted to fit over and snugly engage one of the flanges of the base of the rail. A depending retaining member 17 of inverted T-shape in cross section is integrally formed with each fixed block 15 and is provided with an extension 18 at one end. In assembling a fixed block with a tie, its T-shaped retaining member 17 is inserted through the opening 13 which is of such a size as to permit of its passage and the block is then slid toward the end of the slot 70 remote from the opening 13, the vertical portion of the I-shaped retaining member being accommodated in the slot 12, the horizontal portion thereof being disposed below the top of the tie and having its marginal portions 17a engaged with the under portions of the top of the tie along each side of the slot 12. The extension 18 provided on the retaining member engages under the top of the tie at one end of the slot 12.

Each fastening device also includes an adjustable two-part block, designated generally by 20. Each two-part block 20 comprises a fixed or stationary section 21 and an adjustable or movable section 22. The adjustable or movable section 22 is provided with a rail engaging shoulder 23 adapted to overhang and snugly engage the upper portion of the flange of the base of the rail and it also includes a retaining member 24 of inverted T-shape in cross section. In assembling the adjustable section 22 with the tie, the inverted T-shaped retaining member 24 is introduced through the opening 13 following the placing of the stationary block 15 and the positioning of the rail and after having its retaining member 24 introduced into the opening 13, the section 22 is slid toward the rail so as to bring its marginal portion 25 into engagement with the portions of the under side of the tie which lie along the marginal edges of the slot 12. The section 21 includes a depending bar 26 adapted to snugly fit in the slot 12. One end of this bar is inclined or cut away as indicated at 27, and coacts with a similarly formed end 28 of the slot 12. The opposite end of the bar from the inclined portion 27 is beveled, as at 29 so that the sections may be readily assembled as will presently appear. As clearly shown in Figures 4 and 5 the section 22 is provided with a vertical

groove 30 and section 21 is provided with a similarly disposed tongue 31 adapted to fit in the groove 30 in the assembly. The engaging faces of the sections 21 and 22 are 5 also provided with alined or registering slots, designated at 32 and 33, respectively. In order to assemble the section 21 of the tie, it being understood that the fixed block 15, the rail and the adjustable section 22 10 have been previously positioned, the inclined end 27 of the bar 26 of the fixed section is introduced into the slot 12 and is engaged with the inclined end wall 28 of the slot, following which the section 21 is swung 15 downwardly so as to bring the bar 26 into the slot 12 and to bring its tongue 31 into the groove 30. After the parts have been so adjusted and positioned the slots 32 and 33 are alined and registered to provide a substantially continuous key-way. In the key-way provided by the slots 32 and 33 a tapered key or wedge 35, preferably constructed of wrought iron, is introduced and is driven to such an extent as may be necessary 25 to firmly and securely fasten the rail to the tie. It is to be understood that when the wedge is driven into the slots 32 and 33 it will of course tend to move the sections 21 and 22 away from each other in the slot 12. 30 The section 21 is however held against movement since it engages the end wall 28 of the slot. Thus it is that the section 22 has its rail engaging shoulder 23 urged into binding and clamping engagement with the rail 35 and tends also to move the rail into binding engagement with the shoulder 16 of the fixed block. The wedges 35 are preferably constructed of wrought iron or other metal having the requisite properties to enable it to 40 be bent after the wedge has been driven in the slot 32 and 33 to the desired extent. By bending the ends of the wedge after the same has been properly positioned it is secured in position and molds the parts 45 against accidental displacement. At the same time the wedge may be readily bent back to its original form to permit of ready disassembling of the fastening device and removal of the rail. The improved tie construction and fastening device is adapted to 50 standard and narrow gauge roads and for industrial and mine tracks. It is simple in

its construction and yet strong and durable and adapted to stand up under the uses to which it is put.

55

I claim:

1. In combination, a railway tie having a longitudinally extending slot enlarged adjacent one end thereof and a rail fastener including a fixed lock having a rail engaging shoulder and having a depending retaining member of inverted T-shape in cross section, the retaining member being adapted to be introduced in the opening and to be engaged with the tie along the marginal edges of the slot in the assembled position; a two part block including a fixed section and an adjustable section, said adjustable section being provided with a rail engaging shoulder and having a retaining member T-shaped in cross section, said sections having registering slots and a wedge cooperable with said slots.

2. In combination, a tie having a longitudinally extending slot, and a rail fastener having a fixed block provided with a rail engaging shoulder and having a retaining member cooperable with the slot of the tie, and a two part block including a section having a rail engaging shoulder and a retaining member cooperable with the slot of the tie and a wedge cooperatively associated with the sections of the two part block.

3. In combination, a tie having a longitudinally extending slot and a rail fastener having a fixed block provided with a rail engaging shoulder and having a retaining member cooperable with the slot of the tie, and a two part block including a section having a rail engaging shoulder and a retaining member cooperable with the slot of the tie and a wedge cooperatively associated with the sections of the two part block, said sections of the two part block being provided with an interfitting tongue and groove.

4. A rail fastener including a fixed block having rail engaging means, and a two part block including an adjustable section and a fixed section, the adjustable section having rail engaging means and a wedge cooperative with the sections of the two part block for urging the adjustable section into engagement with the rail.

WILLIAM EZRA DOANE.
